UNITED STATES PATENT OFFICE.

MARION W. JACKSON, OF PHILADELPHIA, PENNSYLVANIA, ASSIGNOR TO EUGENE DESFOSSE, OF PARIS, FRANCE.

DESIGN FOR TAPESTRY OR WALL-COVERING.

51,782.

Specification for Design.

Patented Feb. 19, 1918.

Application filed December 29, 1917. Serial No. 209,591. Term of patent 7 years.

To all whom it may concern:

Be it known that I, MARION W. JACKSON, a citizen of the United States, residing in Philadelphia, Pennsylvania, have invented a certain new, original, and ornamental Design for Tapestry or Wall-Covering, of which the following is a specification, reference being had to the accompanying drawing, forming part thereof, in which the figure is a face view of a portion of a body of tapestry or wall covering, illustrating my new design.

I claim:—

The ornamental design for tapestry or wall covering, substantially as shown.

In witness whereof I affix my signature.

MARION W. JACKSON.
